COMBINED VALANCE AND DRAPERY AND
CURTAIN SUPPORTING MEANS

Virginia S. Lee, Quantico, Va.

Application March 22, 1943, Serial No. 480,070

5 Claims. (Cl. 160—38)

This invention relates to a combined valance and drapery and curtain supporting means, and its primary object is to provide a combination of this nature which may be embodied in a relatively light weight, simple and inexpensive construction, will be sufficiently stiff to stand up and maintain its form and shape, while being sufficiently flexible to permit of its bending to fit different sized windows and will comprise a plurality of easily separable sections so that its effective length may be readily varied to cause it to fit windows of varying widths. It is aimed to embody all of the foregoing features in a construction by means of which a single curtain rod may be caused to support both valance and drapes or valance, drapes and curtains.

Further objects and advantages of the invention will be set forth in the detailed description which follows.

In the accompanying drawing:

Fig. 1 is a view, partly in section and partly in perspective, illustrating the device of my invention.

Fig. 2 is a horizontal sectional view through one end of the curtain rod and associated parts.

Fig. 3 is a fragmentary vertical sectional view, illustrating the manner of supporting both drapes and curtains from a single valance carried fabric web.

Like numerals designate corresponding parts in all of the figures of the drawing.

In carrying out the invention I provide a valance V, comprising two or more plies 5 and 6 of buckram or like strong, stiff material that is flexible enough to permit the valance to be bent at its ends as hereinafter described, but stout enough, when reinforced by the pocket hereinafter described, to stand up and maintain its form when supported upon the single curtain rod 7. This curtain rod is of the conventional flat telescopic form now so widely employed and which comprises inturned ends 8 (only one of which is shown) engageable with conventional brackets 9 on the window frame 10. The inner ply 6 of buckram is shaped to provide the aforesaid pocket 11 into which the sections of the curtain rod are slipped from the opposite ends of the pocket. The valance is completed by an outer facing 12 of ornamental fabric and an inner lining or backing 13, the whole being suitably stitched together at appropriate points by stitching 14.

To make it possible to readily adjust the structure to fit windows of varying widths the valance is weakened by a plurality of vertical weakening

perforations 15 by which the valance is divided into a plurality of separable sections. Additional stitching 14a defines the outlines of the several sections and prevents the cutting of the stitching 14 from bringing about undue separation of the plies of the valance.

To provide means for supporting drapes or curtains or drapes and curtains from the valance so that a single rod may support all of these, I stitch to the rear face of the pocket 11 a web 16 of relatively heavy canvas the lower edge of which depends for a considerable distance below the pocket and which web is provided along its lower edge with a row of openings 17. The openings are of a nature to receive the hooks 18 of drapes 19 or the hooks 20 of curtains 21.

The manner of stitching a relatively stiff canvas web to the back of the pocket 11, as described, has the following important functional advantages: first, it offsets the web 16 from the rear face of the valance enough to facilitate the engagement of the hooks 18 and/or 20 with the openings 17; and, second, since the entire weight of drapes and curtains is suspended from the canvas web, and since this weight tends to maintain said web in a flat vertical plane, it follows that the canvas web resists any tendency of the pocket 11 to twist. Therefore, additional rigidity is imparted to the pocket to cause it to aid the valance in maintaining its upright form despite the fact that it is composed so largely of non-rigid materials, and despite the fact that it is crossed by a plurality of vertical weakening lines of perforations. These weakening lines may be caused to include the pocket 11 or not. It is preferred to leave the pocket free of such perforations, since a woman with a carving knife can readily cut across the width of the pocket when erecting the valance. This preserves the strength and rigidity of the pocket throughout normal conditions of use of the valance.

After the valance is cut off to the approximate width of the window its ends are bent inwardly to house and conceal the inturned ends of the rod and the brackets and said ends are tacked to the window frame as indicated at 22.

I am aware of the fact that it has heretofore been proposed to support drapes from the valances. However, the devices of this nature with which I am familiar are cumbersome and expensive. I know of no prior article having the many advantages of my construction as outlined above. Therefore, it is to be understood that the invention is not restricted to the precise construction illustrated, but that it includes within its pur-

view whatever changes fairly come within either the terms or the spirit of the appended claims.

Having thus described my invention, what I claim is:

1. In an article of the character described, the combination with a valance made of a material flexible enough to be bent at its ends to conform to a rod having inturned ends, the material of the valance being shaped to form an integral pocket extending the full length of the valance and outstanding beyond the rear wall of the valance, a web of relatively heavy woven fabric, such as canvas, stitched to the rear face of the pocket at at least two vertically separated points in the width of the pocket and depending materially below said pocket, and means disposed along the lower edge of said web to receive the suspending hooks of drapes or curtains or both.

2. In an article of the character described, the combination with a valance made of a material flexible enough to be bent at its ends to conform to a rod having inturned ends, the material of the valance being shaped to form an integral pocket extending the full length of the valance and outstanding beyond the rear wall of the valance, a web of relatively heavy woven fabric, such as canvas, stitched to the rear face of the pocket at at least two vertically separated points in the width of the pocket and depending materially below said pocket, said web being provided with a row of openings along its lower edge

through which the suspending hooks of drapes or curtains may be passed in either direction.

3. In an article of the character described, a valance comprising a facing of ornamental fabric, at least two plies of relatively heavy and stiff but bendable material, such as buckram, one of which at least is shaped to form a pocket for the reception of a flat rod, the rear face of said pocket outstanding beyond the rear face of the valance and presenting a substantially plane rear face, a web of material secured to the rear face of the pocket and depending therebelow, said web having a row of openings along its lower edge through which the suspending hooks of drapes and curtains may be passed, the weight of said drapes and curtains then tending to maintain the web in a vertical plane and to maintain the pocket against tipping forward under the weight of the valance.

4. A structure as recited in claim 1 wherein the valance is provided with a plurality of weakening perforations extending vertically thereof at spaced intervals therealong, the areas being defined by rows of stitching through the valance so that each such area is independently stitched.

5. A structure as recited in claim 3 wherein the valance is provided with a plurality of vertical lines of weakening perforations disposed at spaced intervals therealong, which lines skip the pocket.

6. A valance as claimed in claim 3 wherein

the facing is made of VIRGINIA S. LEE.
